his ATTORNEY

UNITED STATES PATENT OFFICE.

JULIUS PEDERSEN, OF BRIDGEPORT, CONNECTICUT.

SHELF-REACHER.

1,350,331.

Specification of Letters Patent Patented Aug. 24, 1920.

Application filed March 29, 1919. Serial No. 286,170.

To all whom it may concern:

Be it known that I, JULIUS PEDERSEN, a citizen of the United States, residing at Bridgeport, in the county of Fairfield and State of Connecticut, have invented certain new and useful Improvements in Shelf-Reachers; and I do hereby declare the following to be a full, clear, and exact description of the invention, such as will enable others skilled in the art to which it appertains to make and use the same.

My invention relates to an improvement in shelf reachers, and it consists in certain details of construction to be more fully set forth in the following specification.

Referring to the accompanying drawings wherein the same figures and letters of reference indicate like parts throughout the several views:

Figure 1 represents a side elevation of the device in its normal inoperative position;

Fig. 2 is a broken view of the pole and actuating rod, showing the position of the handles when the device is being operated;

Fig. 3 is an enlarged broken view of the upper end of pole and actuating rod showing the jaws closed;

Fig. 4 is an enlarged view similar to Fig. 3, except that the jaws are in their normal open position;

Fig. 5 is an enlarged reverse view of the gripping mechanism in open position, and broken view of the pole and jaws;

Fig. 6 is an enlarged cross sectional view of the pole and end view of one of the operating handles; and

Fig. 7 is an enlarged broken sectional view of one of the handles, and broken view of the actuating rod and pole.

The device comprises the pole or other like support 1, which may be of any length required, having the extension 2 secured in its upper end, and terminating in the support upper end, and terminating in the support hook portion 3. 4 are jaws whose shanks 5—6, links 7—8, and rivets 9—10 and 11, form part of a "toggle-arm."

The one piece actuating rod 12 is joined by its upper curved end 12^a to the links 7—8 to complete the toggle arm joint. 13, Fig. 5, is a slot in the extension 2 to provide the necessary vertical movement for the end 12^a. The spring 14, located between the toggle arm and the collar 15 on the pole, serves the

purpose of maintaining the jaws in a normal open position.

16 and 17 are handles pivotally supported on the pole by pins 18—19. The rod 12 is pivotally connected to both handles by means of the reverse bend 20 in the rod passing through the opening 21, Fig. 7, of the upper handle 16, and the hook 22 passing through a similar opening—not shown—in the handle 17.

The hook 3 or the hole 23 of the support 2 may be used in suspending the device when not in use.

Pads 24, of leather or rubber, may be slipped over the ends of the jaws 4 and secured thereto by the bands 25.

When using the device to remove an article from an upper shelf, the lower handle 17 is first depressed, Fig. 2, to bring the jaws in contact with the article, Fig. 3. In case a heavy article is to be removed and the grip of the lower handle is not sufficient for the purpose, the operator's free hand can grasp the upper closed handle to increase the grip.

As the device is being lowered with the article, the hand, gripping the handle 17, is shifted to the upper handle 16 so that the operator has a firm grip on the article during its descent. Any number of these handles, and all pivoted to one rod, may be employed at suitable distances above the lower handle

to be within easy reach of the operator's hands when operating the device. A pole thus equipped with gripping handles at suitable spaced intervals, is available as a carrier for any height within the length of the pole. In other words, the number and location of the handles will enable the operator to shorten or lengthen the reach of the pole to reach and remove articles more readily than if one handle was used and that located at the lower end of the pole.

Having thus described my invention, what I claim is:

1. In a device of the character described, a support, a slotted member extending upwardly from an end of the support, a rod extending lengthwise of the support and having its upper end curved and extending through the slot of said member, a pair of jaws pivoted to the member, and links pivoted to the jaws and pivoted to said curved upper end of the rod.

2. In a device of the character described, a support, a slotted member extending upwardly from an end of the support, a rod extending lengthwise of the support and having its upper end curved and extending through the slot of said member, a pair of jaws pivoted to the member, links pivoted to the jaws and pivoted to said curved upper end of the rod, and a coil spring surrounding the rod and bearing at one end against the curved end of the rod and secured at its opposite end to the support.
3. In combination with a support, a slotted member extending upwardly from the support and having its upper end free and curved outwardly so as to provide a hook for allowing the support to be suspended, jaws pivoted to the member, links pivoted to the jaws, and a rod on the support having a connection with the links operating in the slot of said member.
4. In combination with a support, a pair of jaws pivoted thereto, a rod on the support connected to the jaws for operating same, said rod having a plurality of laterally extending reverse bends at spaced points, and a plurality of handles pivoted to the support and each having an opening, the lowermost bend being hooked into the opening of its handle and the adjacent handle receiving the adjacent reverse bend whereby each handle may independently move the jaws to operative position.

and having parts pivotally connected to the respective bends for independently moving the jaws to operative position.

5. In combination with a support, a pair of jaws pivoted thereto, a rod on the support connected to the jaws for operating same, said rod having a plurality of laterally extending parts at spaced points, and a plurality of handles pivoted to the support and having portions pivoted to said respective lateral parts for independently moving the jaws to operative position.

6. In combination with a support, a pair of jaws pivoted thereto, a rod on the support connected to the jaws for operating same, said rod having a plurality of laterally extending reverse bends at spaced points, and a plurality of handles pivoted to the support and each having an opening, the lowermost bend being hooked into the opening of its handle and the adjacent handle receiving the adjacent reverse bend whereby each handle may independently move the jaws to operative position.

In testimony whereof I affix my signature.

JULIUS PEDERSEN.

DISCLAIMER

1,350,331.—*Julius Pedersen*, Bridgeport, Conn. SHELF-REACHER. Patent dated August 24, 1920. Disclaimer filed May 2, 1934, by the patentee.

Hereby enters this disclaimer to that part of the claim in said specification which is in the following words, to wit:

“1. In a device of the character described, a support, a slotted member extending upwardly from an end of the support, a rod extending lengthwise of the support and having its upper end curved and extending through the slot of said member, a pair of jaws pivoted to the member, and links pivoted to the jaws and pivoted to said curved upper end of the rod.

“2. In a device of the character described, a support, a slotted member extending upwardly from an end of the support, a rod extending lengthwise of the support and having its upper end curved and extending through the slot of said member, a pair of jaws pivoted to the member, links pivoted to the jaws and pivoted to said curved upper end of the rod, and a coil spring surrounding the rod and bearing at one end against the curved end of the rod and secured at its opposite end to the support.”
